MOTOR COMPANY, OF WASHINGTON, DISTRICT OF COLUMBIA, A CORPORATION
OF DELAWARE.

PISTON FOR EXPANSION-ENGINES.

1,159,066.

Specification of Letters Patent.

Patented Nov. 2, 1915.

Application filed January 5, 1912. Serial No. 669,576.

To all whom it may concern:

Be it known that I, ROBERT S. MOORE, a citizen of the United States, residing at Washington, in the District of Columbia, 5 have invented certain new and useful Improvements in Pistons for Expansion-Engines, of which the following is a description, reference being had to the accompanying drawing, and to the letters and figures 10 of reference marked thereon.

The invention relates to new and useful improvements in pistons in general, and more especially to pistons for use in connection with expansion engines, such as gas 15 engines.

An object of the invention is to provide a piston with a device for producing a smooth sliding fit between the piston and the cylinder, which is not liable to cause the 20 piston to bind in the cylinder, or cause undue wear or scoring of the surface of the cylinder by reason of the expansion of the metal in the head of the piston, due to the heat of the expanding gases.

25 A further object of the invention is to provide a piston with a metal ring which is located adjacent the head of the piston, and so constructed that the expanding of the gases will cause the ring to expand and engage the wall of the cylinder, thereby providing a perfect joint between the piston head and the wall of the cylinder.

These and other objects will in part be obvious and will in part be hereinafter more 35 fully described. In the drawings which show by way of illustration one embodiment of the invention:—Figure 1 is a sectional view through a piston head, having my improvements applied thereto, and showing 40 the relation of the same to the wall of the cylinder; Fig. 2 is an edge view of the expansible ring with a part thereof broken away in section to show the construction of the ring; Fig. 3 is a similar view showing 45 the manner in which the ring may be expanded; Fig. 4 is a view similar to Fig. 1, showing a modified form of construction of the ring and the seat therefor; Fig. 5 is a view similar to Fig. 2, of the form of ring 50 shown in Fig. 4; Fig. 6 is a view similar to Fig. 1 showing a still further modification of the ring for forming a tight joint between the piston and the wall of the cylinder; Fig. 7 is an enlarged view showing the

manner in which the ring may tilt; Fig. 8 55 is a plan view of the ring shown in Fig. 6.

In the drawings, I have shown in section the wall of a cylinder 1, which is provided with a plurality of heat radiating ribs. Located within the cylinder, is a piston 2. 60 The piston as herein shown, is provided with a relatively thin head 3, and a cylindrical wall or body portion 4, which engages the inner surface of the cylinder. Said piston head is formed with an opening 5 adapted to receive the valve seat so that the intake may be through the center of the piston. It is obvious however, that this construction of the head forms no part of the 65 present invention, and other forms of piston heads may be used.

The piston is formed with an annular groove 6 which is located adjacent the outer face of the head, and in the outer wall of the cylindrical portion 4 of the piston. Located 75 within the annular groove 6 is a ring 7. This ring 7 is preferably made of cast iron, and is split as at 8, so that the ring may expand slightly under pressure, as shown in Fig. 3. The ring is angular in shape, thus 80 providing a flange 9 which seats in the annular groove, and a projecting rim 10, which extends forwardly, that is, into the expansion chamber.

The inner wall 11 adjacent its forward 85 end is chamfered or inclined so that the extreme edge of the ring is brought to a comparatively sharp edge. This ring 7 rests freely in the annular groove 6, and will be caused through the connection between the 90 flange 9 and the walls of the groove, to move with the piston as it reciprocates in the cylinder.

In the operation of the device, the expansion of the gases in the combustion chamber 95 will exert a pressure against the inner wall of the ring 7, and thereby cause the ring to expand, which expansion is permitted owing to the ring being split, and the outer wall of the ring to make a firm contact with the 100 wall of the cylinder. The expansion of the gases will also cause the flange 9 to seat against the wall of the annular groove and prevent any leakage through the annular groove, and about the piston. By this construction, the piston may be turned so as to have a very free movement in the cylinder, 105 and any expansion of the piston will not

cause a binding of the piston in the cylinder, or a scoring of the wall of the cylinder. While the piston moves freely in the cylinder, the expansible ring will make a perfect 5 contact with the wall of the cylinder, and prevent any leakage of the expanding gases about the piston.

In Fig. 4, I have shown a piston 2 wherein the annular groove 12 for the expansible 10 ring 13 is formed so that the wall 14 is inclined backwardly and the wall of the ring 7, which seats against the wall 14, is similarly inclined. By this construction, the 15 expanding gases in the combustion chamber, not only forces the ring outwardly against the wall of the cylinder, but by forcing the ring against its seat, the inclined walls are caused to contact and to slide one on the other, thus further forcing the expansible 20 ring outward toward the wall of the cylinder.

The operation of the piston, as shown in Figs. 4 and 5, is precisely the same as in Figs. 1 to 3 inclusive, except that the inclined wall increases the effective forcing of 25 the ring against the wall of the cylinder. In Figs. 6 to 8 inclusive, I have shown the expansible ring 15 as made in four sections. The flange 16 projecting inwardly toward 30 the center of the piston head, is also longer. The upper wall 17 of the annular groove 18 in the piston 2, as viewed in Figs. 6 and 7, is inclined downwardly so as to form a fulcrum point 19 in its outer edge. This fulcrum point 19, is slightly outside of the center of weight of the ring. That is to say, the weighted parts of the ring at the left of the fulcrum point 19 in Fig. 7, exceeds 35 slightly the weight of the parts at the right thereof. When this construction is applied to a revolving cylinder engine, the centrifugal force acting upon the ring, will cause the sections of the ring to swing about the fulcrum point 19, and the outer edge 20 to be 40 brought in contact with the wall of the cylinder, as shown in Fig. 6.

By forming the ring in sections, each section may swing or tilt about the fulcrum edge 19, in the manner above described. 50 While I have shown the ring made in four sections, it is obvious that said ring may be otherwise divided, and may be made in two sections, three sections, or any other number of sections. Not only will the sections of the

ring be caused through centrifugal force to 55 properly engage the wall of the cylinder, but the expanding gases in the combustion chamber will further force the outer edge 20 of the ring against the wall of the cylinder.

While I have shown the ring in Figs. 1 to 60 5 inclusive as split on one side thereof only, it is obvious that said ring may be made in sections, and therefore, by the term "split ring", I do not confine myself to a ring 65 which is cut through in one place only.

It is obvious that minor changes in the details of construction, as described, may be made without departing from the spirit of the invention as set forth in the appended 70 claims.

Having thus particularly described my invention, what I claim as new and desire to secure by Letters Patent, is:—

1. A piston comprising a body portion 75 having an annular groove in the side face thereof adjacent the head, and a single split ring having an inwardly projecting retaining flange substantially fitting said groove, and an integral annular projection extending toward the outer face of the piston head, 80 the inner wall of said annular projection being inclined relative to the outer wall thereof so as to form a substantially sharp outer edge, said flange being adapted to freely seat in the annular groove, whereby the expansion of the gases in the combustion chamber will cause said ring to expand and the outer wall thereof to contact with the wall 85 of the cylinder.

2. A piston comprising a body portion 90 having an inclined annular groove in the side face thereof adjacent the head, an expansible ring having an inwardly projecting flange loosely fitting said groove, and an annular projection extending toward the outer 95 face of the piston head, whereby the expanding of the gases in the combustion chamber forcing the ring against its seat will force the outer surface of the ring against the wall of the cylinder and cause the upper and 10 lower faces of the flange to firmly engage the upper and lower walls of the groove.

In testimony whereof I affix my signature, in presence of two witnesses.

ROBERT S. MOORE.
